UNITED STATES PATENT OFFICE.

HAROLD ROBERT SUITER, OF GRAND RAPIDS, MICHIGAN.

MOLD-FORM STRUCTURE.

Application filed August 2, 1927. Serial No. 210,199.

This invention relates to forms or molds by means of which concrete or other plastic material is shaped to form walls and other similar structures, and constitutes an improvement over the type of construction illustrated in my prior United States Letters Patent, No. 1,574,636.

Briefly stated, the present invention provides as an important feature, a corner mold form characterized by the employment of angularly disposed converging articulated side wall sections terminating at either side of the corner angle extremity, these sections being completed by an angle member presenting a vertically extending filler of approximate V-shape in cross section forming the corner angle of the mold and constituting a continuation of the adjacent side sections. Bracing means are employed to support and maintain the filler in cooperative relation to the side sections.

As an additional feature, the invention provides means for alining and joining abutting or superposed sections of the mold, one form of which provides means for bracing that section of the mold to which it is attached.

Other objects and advantages will be apparent during the course of the following description.

In the drawings accompanying and forming part hereof and in which a preferable embodiment of the invention is illustrated:

Fig. 1 illustrates a corner mold structure of the present invention with upper and lower superposed corner sections shown separated to disclose the cooperative arrangement and interior features.

Fig. 2 is a top plan view of such a mold used in connection with adjacent ends of a building under construction and illustrating the manner of bracing the corner angle members.

Fig. 3 is a vertical section on an enlarged scale taken on the line 3-3 of Fig. 2.

Fig. 4 is a horizontal section on an enlarged scale through one of the corner angle members illustrating the coaction of its filler with the adjacent side wall sections of the mold.

Figs. 5 and 6 illustrate different forms of anchoring abutments for the lower ends of turn-buckle braces.

The illustrated articulated mold is of the

type illustrated in my prior patent above referred to, the articulated sections comprising parallel form boards 2 arranged in horizontal courses based upon a suitable support such as the foundation 1 and held in alinement, and against disalinement through 55 pouring, by tie wires 3 in the form of elongated loops extending between adjacent courses at appropriate points with their ends projecting beyond the outer faces of the form boards 2 as at 4, and locked in position by a series of vertical locking rods 5, the projecting ends 4 of the tie wires being, 60 of course, in vertical alinement. So far as the purposes of the present invention are concerned, the particular form of tie wire is 65 immaterial.

In a corner mold with which the present invention is more particularly concerned, the articulated side wall sections of the mold are disposed in converging angular relation 75 to provide the corner mold structure. The inside mold board members of this structure, which as seen in Fig. 1, are braced adjacent their meeting angle by tie wires and locking rods, have their complemental side members brought together so as to abut, as at 6 and 7, this junction of the sections providing the inside corner of the mold. It is not necessary to provide a finished edge at this point, but at the outer side of the mold, a 80 finished corner angle is highly desirable. In accordance with the present invention, the outer converging side walls of the mold terminate at opposite sides of the outer corner extremity of the mold structure and a separate filler is provided for this portion of the mold. One form which this filler may take, provides a unitary angle member projecting outwardly from the corner of the mold with divergent angular sides 8 and 9 braced by triangular cleats 10 and having 85 connected appropriately to their inner edge, a vertically extending V-shaped filler 11 alining with the converging outer side wall sections of the mold to form a continuation 90 thereof and the outer corner angle of the mold. The base of this angle member is fixed in proper position in the mold structure by appropriate means. In the drawings, in the lower section of the mold in 95 which the base courses rest upon the foundation 1, blocks 12 at the outer sides of the angle boards 8 and 9 of this member are

appropriately anchored to the base or foundation 1 in positions defining the proper position for the base of the angle member which may be secured to these blocks 5 through nails or screws inserted through these angle members.

Where in pouring a wall corner, it is desired to pour an additional section before a lower section has been set, a second mold 10 section, as shown in Fig. 1 of the drawings, is superposed over the base section. The side wall sections of these two superposed units will be alined through the employment of longer locking rods 5 and in order to secure 15 the angle members 8-9 of the upper section to and in alinement with the lower angle members, joint plates of novel construction are provided. As shown in Fig. 1 at the upper portion of the lower section of 20 the mold, the top edges of the angular sides 8-9 of the angle members are embraced by substantially U-shaped plates 13 bolted through the sides thereof and provided with upstanding pins or dowels 14. The base of 25 the superposed angle members 8-9 will be embraced at alined points by similar U-shaped plates 15 bolted thereto and having sockets 16 formed therein to receive the dowels 14 of the section next below. The joint 30 plates 13, being positioned upon the divergent sides of the angle members will unite these superposed members in proper alinement, the adjacent side mold sections being similarly alined through the rods 5.

35 The upper U shaped joint plates 13 for embracing the upper edges of the divergent sides 8 and 9 of the angle members of the mold form section are formed, as best seen in Figs. 2 and 3, with bifurcated offsets 17 forming ears between which eyes 18 are journaled. These eyes serve as pivot links to which the upper bifurcated ends of turn-buckle brace rods 19 are pivotally connected. These brace rods extend from the outside 40 of the divergent sides 8-9 of the angle members diagonally downward in opposite directions, their lower ends being anchored to a suitable abutment, which as is shown in Figs. 5 and 6 and in Fig. 1, may be 45 formed by the head of a bolt or nail 20 extending in or through a tube 21 spacing the lower courses of the inner and outer wall sections of the mold, the lower section of the turn-buckle being formed as an eye 22 50 through which the bolt or nail anchor 20 extends.

In the lower half of Fig. 1 of the drawings, a modified form of a bracing member is shown, this form constituting diagonal 60 brace bars or boards 23 nailed to the outer edges of the divergent side angle members 8 and 9 and similarly anchored at their bases to blocks 24 which in turn are anchored to the base support 1. While this form may 65 be used on the base section, the turn buckle

brace previously described is of a more permanent nature and is equally applicable to the lower course of the mold structure.

The angle members forming the corner angle of the mold, as described, therefore 70 constitutes a movable mold corner element, which may be moved from installation to installation and used over and over again. The corner and edge molding surface provided by its V-shaped filler piece will 75 present an unbroken line or surface throughout its height, and a smooth edge finish for the corner can be secured.

When a corner is first poured and the side walls are next to be extended, it is desirable 80 to provide the poured side walls with some shoulder or abutment to which the next section poured may be joined. I have secured this result and improved the molding operation by providing end closures for the side 85 sections of the corner mold form, these mold corners being in the form of filler mold boards 25 sized and shaped to close the ends of the mold sections and provided on their inner sides with groove-forming ribs 26, the 90 outer edges of the filler being both braced and fixed in position by vertical cleats 27. The end closure described will form with its rib 26, a groove in the poured section of 95 the mold which when set will provide shoulders against which the concrete in the next poured section will abut and set. While I have herein described a specific embodiment of the invention, it will be understood that 100 various modifications and adaptations thereof will be permissible within the spirit of the invention and the scope of the appended claims.

What I claim therefore, and desire to secure by Letters Patent is:

1. A corner mold form comprising complementary inner and outer side sections extending in converging angular relation and having their ends at the inner side of the mold form overlapped to form the inner corner of the form and with their ends at the outer side of the mold form terminating at either side of the outer corner of the form, and a corner filler comprising a separate unitary corner structure providing an inner vertical V member having its sides alined with the adjacent outer side sections and abutting their edges to form a continuation thereof and having outwardly extending portions in angular relation, and diagonal braces connected to said outwardly extending portions to brace and maintain said member in vertical alined position.

2. A corner mold form comprising complementary articulated spaced side sections 125 extending in converging angular relation and having their ends at the inner side of the mold form overlapped to form the inner corner of the form and with their ends at the outer side of the mold form terminating 130

at either side of the outer corner of the form, and a corner filler comprising a separate unitary corner structure providing a **V** member having its sides alined with the adjacent outer side sections and abutting their edges to form a continuation thereof and provide the outside corner angle of the mold, said filler having a base support and bracing means for its upper end maintaining it in cooperative alinement with the adjacent articulated sections of the mold form.

3. A corner mold form comprising articulated side sections terminating at either side of the corner extremity and a braced unitary angle member at the corner of the form extending outwardly therefrom and presenting an inner vertically extending **V** shaped filler portion alined with the sides of the adjacent side sections and abutting their edges to form a continuation thereof and provide the corner angle of the mold.

4. A corner mold form comprising articulated spaced side sections arranged in superposed courses with their inner corner edges overlapped and joined and with their outer side section courses terminating at either side of the outer corner angle extremity, and braced angle members arranged in vertical courses and extending outwardly from the mold with inner **V** shaped filler portions alined with the adjacent side sections to form a continuation thereof and the corner angle of the mold, superposed angle members having their abutting ends interlocked in alinement.

5. A corner mold form comprising complementary articulated side sections extending in angular relation and a separate corner filler comprising an angular member providing at its inner side a **V**-shaped filler portion with sides in alinement with and abutting the adjacent side sections to form a continuation thereof and the corner angle of the mold, a support for the base of said angle member and oppositely disposed diagonal brace members connected to and extending from its upper portion to support and maintain said angle member with its filler portion in cooperative alinement with the adjacent side sections.

6. A corner mold form comprising complementary articulated side sections extending in angular relation and arranged in horizontal courses with the ends of the sections at the inner side of the form abutted to form the inside mold corner and the ends of the outside sections terminated at either side of the outside corner extremity, and a separate unitary angle member braced at base and top and presenting an inner **V**-shaped filler portion alined with and forming a continuation of the adjacent side sections and providing the outside corner angle of the form.

7. A corner mold form comprising complementary articulated side wall sections ex-

tending in converging angular relation with the adjacent edges of the outer side wall sections and terminating at opposite sides of the corner extremity, an angle member having its inner face provided with a vertically extending **V**-shaped filler portion abutting the edges of and forming a continuation of the outer side wall sections and providing the outer corner angle of the mold, means to support and position the base of said angle member, corner brackets secured to the opposite sides of said member at its top, and turn-buckles at opposite sides of the angle member anchored to said brackets and to a stationary abutment to position and hold the angle member with its filler in cooperative alinement with the side wall sections.

8. In a corner mold form, an angle member forming the corner angle of a mold form and comprising outwardly diverging angular sides terminating at their inner conjoined ends in a vertical **V**-shaped filler forming a continuation of the sides of the mold and providing the corner angle thereof.

9. In a corner mold form, a plurality of vertically superposed angle members providing **V**-shaped fillers in vertical alinement and forming continuations of the sides of the mold and the corner angle thereof, said superposed angle members having outwardly divergent sides and means mounted upon the divergent sides of abutting angle members providing interengaging dowel and socket members to maintain the angle members in vertical alinement.

10. In a mold form, abutting mold sections to be joined and maintained in alinement and connecting means therefor comprising section embracing plates having aligned pin and socket connections.

11. In a mold form, abutting mold sections to be joined and maintained in alinement and connecting means therefor comprising section embracing plates having aligned pin and socket connections, and having a brace rod connection.

12. In a mold form, abutting mold sections having edge embracing plates mounted thereon in alinement and having doweled connections to align the sections, one of said plates having an offset thereon, and a turn-buckle brace rod connected at one end to said offset and extending to anchoring abutment.

13. A junction plate for mold sections comprising a substantially **U**-shaped edge embracing plate adapted to be anchored to a mold section and having an offset for bracing.

14. A junction plate for mold sections comprising a substantially **U**-shaped edge embracing clamp having a section joining dowel connection and an offset constructed for attachment thereto of a brace.

15. A corner mold form comprising complementary side sections extending in converg-

ing angular relation and terminating at either side of the corner extremity and a unitary angle member at the corner of the form having an inner vertically extending V-shaped filler portion alined with the sides of the adjacent side sections and abutting their edges to form a continuation thereof,

and having wings extending outwardly therefrom in divergent angular relation, and inclined braces connecting said wings with the adjacent side mold sections to brace and maintain said corner angle member in its vertical alined position.

10

HAROLD ROBERT SUITER.
